UNITED STATES PATENT OFFICE.

EDWARD TEMPLE, OF SYDNEY, NEW SOUTH WALES, AUSTRALIA.

GAS-PURIFYING APPARATUS.

977,907.

Specification of Letters Patent.

Patented Dec. 6, 1910.

Application filed November 30, 1908. Serial No. 465,311.

To all whom it may concern:

Be it known that I, EDWARD TEMPLE, a subject of the King of Great Britain, residing at 63 Pitt street, Sydney, in the State of New South Wales, Australia, have invented certain new and useful Improvements in Gas-Purifying Apparatus; and I do declare the following to be a full, clear, and exact description of the invention, such as will enable others skilled in the art to which it appertains to make and use the same.

My invention relates to gas purifying apparatus and provides means for automatically drawing gas from the generator, washing and purifying same and delivering it under pressure.

In order that my invention may be the more easily understood reference may be made to the accompanying drawings, in which—

Figure 1 is a sectional elevation of apparatus embodying my invention. Fig. 2 is a section on the line *a—a* Fig. 1. Fig. 3 is a section on the line *b—b* Fig. 1. Fig. 4 is a side elevation of one of the washers, while Fig. 5 is a section on the line *c—c* Fig. 4.

In these drawings, which show a plant having a duplex set of scrubbers and washers, 1 is a generator standing on blocks 2 in a pan 3 and having fire bars 4 and a fuel hopper to be hereafter described. Beneath the fire bars is a plate 6 at about the water level *z—z* having segmental openings 7 and a plate 8 operated by a rod 9 for adjusting the position of the plate 8 relatively to the segmental openings 7.

10 is a door having a regulatable shutter opening 11 for the supply of air to the furnace.

12 (Fig. 4) are the outlet pipes discharging on to the surface of the water under the bells 13.

14 are outlets from the bells.

15—15 are scrubber cylinders standing in the pan 16 having tar traps 17 and cooling chambers 18.

19 (Figs. 1 and 2) is a vessel having a vertical partition 20 extending from the top to a point some distance from the bottom whereby the vessel is divided at its upper part into two compartments 21 and 22. In the compartment 21 is a frame 23 in which is mounted toward the top an axle 24 carrying sprocket wheels 25 and toward the bottom axles 26 carrying sprocket wheels 27. On these wheels sprocket chains 28 run on

which are mounted axles 29 carrying buckets 30 the buckets being provided with stop pieces 31 to prevent undue swinging on the axles. Above the axles 26 is a director plate 32 leading to the compartment 22.

33 is the gas inlet from the scrubber cylinders 15 to the compartment 21.

The compartment 22 is shown packed with pieces of coke, flint, pebbles or the like 34 resting on a perforated tray 35 to normal water level *y—y*.

36 is the purifier and drier containing cotton, saw-dust, lime or other suitable material.

The axle 24 before mentioned is operated from a shaft 37 driven by any suitable means.

58 is a tar tank to receive tar from the vessel 19 and 65 and 66 are water gages for showing the water level in the two compartments 21 and 22.

68 (see Figs. 4 and 5) is an overflow-pipe carrying off impure water, which delivers to the pipe 69.

The pipe 41 leads from the purifier 36 to a water-locked vessel 42 containing water to the level *x—x*. This vessel is covered and has a gas outlet pipe 43, leading to the engine and the central pipe 44. The pipes 41 have their openings below water level. A by pass 45 with tap 46 is provided between the pipes 41 and 43 and a tap 67 on the pipe 43 for drawing off samples of gas for testing purposes.

The hopper for introducing the fuel to the generator consists of a cylindrical chamber 47 turning fairly closely in a casing 48 arranged on the top of the generator 1. The casing has an opening 49 at its upper part and an opening 50 of larger size than the opening 49 extending some distance into the furnace which opening is provided at the lower part with hinge doors 51 held normally in a closed position by weights 52. The chamber 47 has an opening 53 larger than the opening 49 but smaller than the opening 50; it has also a handle 54 for revolving same.

In operation the fire being started in the generator the gas is allowed to pass through one set of scrubbers and washers and the shaft 37 is set in motion. The buckets 30 on chains 28 will be moved in the direction shown by the arrows (Fig. 2) and will draw gas from the generator to above the water in the compartment 21, convey it beneath

same and discharge the gas under the director plate 32 on passing around the first set of sprockets 27. The gas is led by the director plate to the chamber 22 where it passes up through the coke 34 and water to the purifying and drying chamber 36 from which it passes to the water lock 42 pressing water up the pipe 44 in same and exposing the opening to the pipe 43 whereby the gas 5 may pass to the engine. As gas collects in the top of the compartment 22 and the purifier 36 pressure will be raised, the water level in the compartment 22 depressed and that in the compartment 21 raised, by which 10 the buckets will be further covered and consequently will carry less gas to the second compartment, whereby the suction and production of gas will be regulated.

By drawing off all the water from the 20 chamber 19 the apparatus may be converted into a suction plant in which the gas will be drawn from the generator 1 through the scrubbers 15 and chamber 19 by the suction of the engine. In this case the chamber 19 25 will act as a separate scrubber.

Although I have described and illustrated a plant having a duplex set of scrubbers, washers and purifiers, this being the arrangement I prefer, it is obvious that in 30 some cases only one set might be used, and as will be understood, the parts of the duplex apparatus may be operated simultaneously or alternately as may be desired.

I claim as my invention:—

35 1. In a gas purifying apparatus, a vessel divided into two communicating compartments constructed to be partially filled with water, a series of buckets, means for moving the said buckets within the said compartments in such a manner that the gas above 40 the water therein will be conveyed from the upper portion of the compartment to a point beneath the water where the gas is released and caused to escape to the other or second 45 of said compartments, and a body of coke

pebbles or the like in said second compartment and through which the said gas is caused to pass after entering this second compartment.

2. In a gas purifying apparatus, a vessel 50 divided into two communicating compartments constructed to be partly filled with water, sprockets mounted in one of said compartments, chains passing over the said sprockets, buckets carried by the said chains 55 for conveying the gas from the upper portion of the said compartment above the water therein to a point beneath the water therein where the said gas is released and caused to escape to the other of said compartments and a body of coke pebbles and the like in the said second compartment and through which the said gas after entering the same is caused to pass.

3. In a gas purifying apparatus, a vessel 65 divided into two communicating compartments constructed to be partly filled with water, sprockets mounted in one of said compartments, chains passing over the said sprockets, buckets carried by the said chains 70 for conveying the gas from the upper portion of the said compartments above the water therein to a point beneath the water therein where the said gas is released and caused to escape to the other of said compartments, a body of coke pebbles and the like in the said second compartment and an auxiliary vessel placed above the aforesaid vessel and into which the said gas passes after passing through the said body of coke 75 pebbles and the like in the said second compartment.

In testimony whereof I have signed my name to this specification in the presence of two subscribing witnesses.

EDWARD TEMPLE.
